UNITED STATES PATENT OFFICE.

CLARKSON A. DISBROW, OF NEW ROCHELLE, NEW YORK, ASSIGNOR TO THE RAIL JOINT COMPANY, OF NEW YORK, N. Y., A CORPORATION OF NEW YORK.

TRACK-LINING DEVICE.

Application filed July 2, 1923. Serial No. 649,127.

To all whom it may concern:

Be it known that I, CLARKSON A. DISBROW, citizen of the United States, residing at New Rochelle, in the county of Westchester and 5 State of New York, have invented certain new and useful Improvements in Track-Lining Devices, of which the following is a specification.

This invention relates to track lining devices for shifting the rails of track to proper alignment with a minimum disturbance of the ballast and without disturbing the track fastenings.

A general object of the invention is to provide a simple and practical tool which meets all requirements of use and which is susceptible of being operated in a safe and expeditious manner with a minimum amount of labor. The relining of railroad tracks 10 frequently presents difficulties to be overcome to effect a proper seating or footing principally on account of the kind and amount of ballast involved and of obstructions such as water-pans, guard-rails, etc. 15 Therefore, the present invention aims to provide a track lining device which may be successfully positioned and operated, although the positioning is confronted with the objectionable conditions above enumerated.

Another object of the invention resides in the provision of a rail bearing lever having a shiftable fulcrum and adapted to be positioned directly below the rail so as to permit the rail bearing lever to be shifted from one fulcrum point to another in succession as the rail is shifted, and without appreciably lifting said rail.

A further object is to provide a track lining device including a base which is provided with a plurality of bearings for the rail bearing lever, the bearings being disposed in a plane below the base so as to permit the ready insertion of the device under a rail although the ballast extends in close proximity to said rail.

With these and other objects in view which will be readily understood as the nature of the invention is more fully explained, the latter consists in the novel construction, combination and arrangement of parts hereinafter more fully described, illustrated and claimed.

A preferred and practical embodiment of

the invention is shown in the accompanying drawings, in which

Figure 1 is a top plan view showing one form of my improved track lining device.

Fig. 2 is a side elevation of the device showing the application thereof.

Fig. 3 is a side elevation of the device the parts being arranged in compact form for the purpose of shipment or the like.

Fig. 4 is a detail sectional view taken on the line 4—4 of Fig. 3.

Fig. 5 is a detail side elevation showing a modified form of the invention, and

Fig. 6 is a detail top plan view thereof.

Similar reference characters designate corresponding parts throughout the several figures of the drawings.

In its general organization the present track lining device includes a base A having a suitable forwardly located anchoring element B, a rail bearing or shifting lever C, 75 and an operating lever D.

Referring to the details of construction of the form illustrated in Figures 1 to 4, inclusive, the base A consists of a relatively flat body 5 preferably formed on its underside with marginal and transverse strengthening ribs 6 and 7 respectively. This base may be made of either malleable iron or pressed steel and is formed at its inner end with a depending self embedding anchoring means B which in this instance is in the form of a claw of spade-like form having a penetrating point 8 which assists the device in seeking its own embedment in the ballast.

The base is provided adjacent its inner end, and in this instance adjacent the claw B, with a plurality of bearing seats for the rail bearing lever C, these seats being formed in a longitudinal series. In order to permit the device to be readily inserted under a rail, although the track may be fairly filled with ballast, and yet permit of the successive functioning of the rail bearing lever, I have provided the bearing seats in a plane below the base.

In the form illustrated in Figures 1 to 4, said bearing seats are located in a depressed portion of the base. The base is formed with an opening 9 preferably located centrally between its side edges and the base on opposite sides of the opening 9 is depressed to form bearing lugs 10—10, each lug being formed with a set of the transversely dis-

posed bearing seats 11, 12 and 13, respectively, which open upwardly.

The rail bearing lever 9 is offset at its forward end as indicated at 14 to provide a toe 15. The lower end of the toe 15 is provided with bearing lugs 16-16 which are adapted to be successively positioned in the bearing seats 11-11, 12-12 and 13-13, the positioning being made in the order named. Due to the fact that the bearings open upwardly, the rail bearing lever may be readily detached whenever so desired.

In order to operate the rail bearing lever C the device is provided with the operating lever D, which in this instance comprises a cam 17 having a socket for receiving a crowbar 18 or other tool which may be used as a lever handle. The cam 17 is adapted to be successively fulcrumed at one end of its arc 20 against any one of a series of bearing shoulders 19 formed on the upper face of the base 5 and located adjacent the outer end of the latter.

In operation the base is positioned in the ballast under the track in such a manner that the bearings 11, 12 and 13 for the rail bearing lever C are located directly under the rail. The rail bearing lever C is then placed in the outermost bearings 11+11 and the said lever C is engaged with the rail flange by means of the operating lever D, the lever C functioning to shift the rail with a minimum amount of lifting action. The operating lever D is successively actuated while 35 in the respective bearings 19 so as to gradually shift the rail. After the maximum movement has been imparted to the rail through the medium of the lever being fully crumpled in the bearing seats 11, the lever C 40 is then disengaged from the rail and fully crumpled on the bearings 12+12, after which the operating lever D is again actuated. The rail bearing lever C is again shifted to the bearings 13+13 and again actuated by 45 the operating lever D. Thus, the rail will be ultimately shifted to its desired position without the necessity of shifting the base A of the device.

In the form illustrated in Figures 5 and 6, the base 20 is provided with an opening 21 for the fulcrum end of the rail-bearing lever E. The base 20 is formed with depending bearing lugs 22-22 and extending across and supported by the lugs 22-22 is a plurality of bearing pins 23, 24 and 25, said pins extending across the opening 21. The lower end of the rail-bearing lever E is formed with a fulcrum seat 26, adapted to receive the fulcrum end of the rail-bearing lever E.

be successively engaged with the bearing pins 23, 24 and 25 in the operation of the device embodying this construction. The same steps are involved as described in connection with the other form of the invention.

65. From the foregoing it will be apparent

those skilled in the art that the present invention is primarily intended to provide for additional throw of the track without disturbing the original seating of the liner. In liners employing a fixed fulcrum point for the track throwing arm it is necessary, after reaching the limit of throw to take up the liner and advance it in order to get additional throw by manipulating the lever C. This not only requires time but disturbs the ballast, thus loosening it so that the liner in its new position does not have the holding or ballast gripping power that it acquired in its original seating. 70 73

Referring to Figure 3 of the drawings, it is pointed out that when the liner is placed with the lever arm bearing in the fulcrum socket 11 and all of the throw that this position will allow has been made, the lever C may then be advanced to the sockets 12 and 13 without disturbing the seating of the base A in the ballast. This is important, because as previously indicated, the ballast

becomes compact by the operation of the liner so that its holding power is increased and it is therefore very desirable that it should not be disturbed. Furthermore, it is sometimes found that in certain kinds of ballast, as for example, ballast that does not compact readily, comparatively little throw can be obtained with the arm C fulcrumed at a fixed point. In that case as the cam D is advanced notch by notch on the base plate and the throwing arm or lever C advances toward a vertical position there is not sufficient load on the base plate to hold it against moving backward. However, this difficulty is obviated by the present invention by making it possible to repeat the operation without disturbing the base in the ballast thereby obtaining additional throw simply by removing the cam D from its notch, advancing the lever arm to one of the more forwardly located fulcruming sockets and then pressing the cam again at the rear of the plate and repeating the operation of throwing. In this way the ballast is kept beneath the base in a confined and compact condition due to the downward

Without further description it is thought that the features and advantages of the present invention will be readily apparent and it is of course understood that changes in the form, proportion and minor details of construction may be resorted to without departing from the spirit or scope of the appended claims.

1. A track lining device including a base having a depression provided with an open bearing seat, a rail shifting lever removably positioned in said open seat and means for operating said lever.

12. A track lining device including a base, 13

- a rail shifting lever whose pivot detachably interlocks with said base and means for operating said lever.
3. A track lining device including a base having a depression provided with a plurality of bearing seats, a rail shifting lever whose pivot is adapted to have a progressive fulcruming engagement in said bearing seats and means for operating said lever.
- 10 4. In a track lining device, a base adapted to have its inner end projected under a rail and provided with a longitudinal series of bearings, a rail bearing lever adapted to be fulcrumed successively on said bearings and means for operating said bearing lever.
5. In a track lining device, a base adapted to have its inner end projected under a rail and provided with a longitudinal series of bearings disposed in a plane below the base, 20 and a rail bearing lever adapted to be fulcrumed successively on said bearings.
- 25 6. In a track lining device, a base adapted to have its inner end projected under a rail and provided with a longitudinal series of bearings, an upwardly bowed rail bearing lever adapted to be fulcrumed successively on said bearings, and means for operating said lever.
- 30 7. In a track lining device, a base adapted to have its inner end projected under a rail and provided with a longitudinal series of bearings disposed in a plane below the base, and an upwardly bowed rail bearing lever adapted to be fulcrumed successively on said bearings.
- 35 8. In a track lining device, a base adapted to have its inner end projected under a rail and provided with a depressed portion formed with a longitudinal series of bearings, and a rail bearing lever adapted to be fulcrumed successively on said bearings.
- 40 9. In a track lining device, a base adapted to have its inner end projected under a rail and provided with a depressed portion formed with a longitudinal series of bearings, and an upwardly bowed rail bearing lever adapted to be fulcrumed successively on said bearings.
- 45 10. In a track lining device, a base adapted to have its inner end projected under a rail and provided with a longitudinal series of bearings, a rail bearing lever adapted to be fulcrumed successively on said bearings, and an operating lever for said rail bearing lever fulcrumed on the base.
- 50 11. In a track lining device, a base adapted to have its inner end projected under a rail and provided with a longitudinal series of bearings, a rail bearing lever adapted to be fulcrumed successively on said bearings, said base being formed with a second series of bearings, and an operating lever adapted to be successively fulcrumed on the bearings of the second mentioned series and operating against the rail bearing lever.
- 55 12. In a track lining device, a base adapted to have its inner end projected under a rail, said base being provided with two sets of bearings, the bearings of each set being arranged in a longitudinal series, the bearings of one set being disposed below the plane of the base, the bearings of the other set being disposed above the plane of the base, a rail bearing lever adapted to be fulcrumed successively on the bearings disposed in the plane below the base, and an operating lever adapted to be fulcrumed successively on the bearings of the set disposed above the plane of the base.
- 60 13. In a track lining device, a base adapted to have its inner end projected under a rail, said base being provided with two sets of bearings, the bearings of each set being arranged in a longitudinal series, the bearings of one set being disposed adjacent the inner end of the base and in a plane therebelow, the bearings of the other set being disposed above the plane of the base and adjacent the outer end thereof, a rail bearing lever adapted to be fulcrumed successively on the bearings disposed in the plane below the base, and an operating lever adapted to be fulcrumed successively on the bearings of the set disposed above the plane of the base.
- 65 14. A track lining device including a base, and track throwing means including a rail bearing lever and an operating lever for the rail bearing lever, each of said levers having a shiftable fulcrum on said base, the fulcrums for the rail bearing lever being located adjacent the inner end of the base and disposed below the plane of said base.
- 70 15. A track lining device including a base, and track throwing means including a rail bearing lever and an operating lever for the rail bearing lever, each of said levers having a shiftable fulcrum on said base, the fulcrums for the rail bearing lever being located adjacent the inner end of the base and disposed below the plane of said base, the fulcrums for the operating lever being located adjacent the outer end of the base and disposed above the plane of said base.
- 75 16. A track lining device including a base having a self seating anchoring means, said base being provided adjacent its inner end with a longitudinal series of bearings, a rail bearing lever adapted to be fulcrumed successively on said bearings, and means for operating said lever.
- 80 17. A track lining device including a base having a self seating anchoring means, said base being provided adjacent its inner end with a longitudinal series of bearings disposed in a plane below said base, and a rail bearing lever adapted to be fulcrumed successively on said bearings.
- 85 18. A track lining device including a base terminating at its inner end in a downturned self embedding anchor, said base being pro-

provided intermediate the anchor and the outer end thereof with a longitudinal series of bearings; a rail-bearing lever adapted to be fulcrumed successively on said bearings and means for operating said lever.

19. In a track lining device, a base adapted to have its inner end projected under a rail and provided with a longitudinal series of bearings; a readily detachable rail bearing lever adapted to be fulcrumed successively on said bearings, and means for operating the bearing lever.

20. In a track lining device; a base adapt-

ed to have its inner end projected under a rail and provided with a longitudinal series of bearings disposed in a plane below the base, and a readily detachable rail bearing lever adapted to be fulcrumed successively on said bearings.

In testimony whereof I hereunto affix my signature in the presence of two witnesses.
